QUICK-ACTING SWITCH MECHANISM

Robert H. Bentley, Hartford, Conn., assignor to
The Arrow-Hart & Hegeman Electric Com-
pany, Hartford, Conn., a corporation of Con-
necticut

Application November 9, 1943, Serial No. 509,603

4 Claims. (Cl. 200—76)

1

This invention relates to snap action electric switch mechanisms. More particularly, it relates to a mechanism suitable for multi-pole electric switches wherein it is desired to break simultaneously each of the multiple lines controlled by the switch.

It is an object of my invention to provide an improved electric switch mechanism particularly adapted for use in multi-pole electric switches of low alternating current ratings.

Another object of the invention is to provide an improved switch mechanism which will cause simultaneous break in all the lines controlled by the switch and which may be economically constructed and assembled.

Another object of the invention is to provide an economical structure for an electric switch of small size for use in multi-circuit arrangements, in which the breaks in all of the lines shall occur simultaneously and which will have a substantial interrupting capacity in comparison to its small size.

Other objects and advantages of my invention will become apparent as it is described in connection with the accompanying drawing.

In the drawing—

Fig. 1 is a longitudinal section view through the center of an electric switch mechanism embodying the invention;

Fig. 2 is a section view similar to Fig. 1, but with parts in closed-circuit position;

Fig. 3 is a transverse section view, the section being taken along line 3—3 of Fig. 2;

Figs. 4, 5 and 6 show, in exploded perspective, certain parts of the mechanism for operating the movable contact.

Referring to the drawing, the switch contacts and terminals are mounted within a rectangular molded insulating base 10 hollowed out for the reception of three identical sets of contacts located in parallel chambers 12, 14, 16, which are separated by longitudinally extending partitions 13 and 15 formed integral with the base.

Each of the contact sets comprises a pair of fixed stamped bar contacts 20, 22 secured upon ledges 24, 26 at opposite ends of the base by hollow internally-threaded rivets 28 which project through the bottom of the base to receive terminal screws 30. Each of the fixed contacts 20, 22 extends into a cavity such as 14c in the central part of each of compartments 12, 14 and 16, and has a conventional highly-conductive button-like contact tip facing downwardly into the cavity for engagement with similar contact tips on a movable bridging contact bar 38 which

2

is normally spring-pressed upwardly into engagement with the fixed contacts by coiled compression spring 40 between the bridging contact and the bottom of the cavity.

3 In order to insulate the bridging contact from the mechanism for operating it to open circuit position, an insulating plunger member 42, preferably made of molded insulating material, rests upon the top surface of each bridging contact 10 and is guided in its movement by channels formed in the side walls of the base and of the partitions 13 and 15.

Because the several sets of fixed and movable contacts are individual units and ordinarily 15 would not be dependent on one another for movement in unison, it has been found needful to provide actuating mechanism for causing simultaneous opening and closing movement of the contacts in order to avoid excessive arcing 20 between the contact surfaces. To accomplish this object, I have provided a frame or contact-moving member made up of three similar parallel stamped sheet metal ribs 50, 52 and 54, each having laterally-directed arms 50a, 52a, 54a at 25 their ends. These arms are each provided with a pair of small neighboring apertures through which pass parallel pins 56, 58, which are, or may be, soldered or otherwise affixed to the arms of the ribs 50, 52, 54 to form a rigid unit. Between 30 the neighboring pins 56, 58 the ends of a leaf spring member 60 are inserted. This member 60 may be stamped from thin resilient sheet metal in the form indicated best in Fig. 6. To accommodate the arms 50a, 52a, 54a, slots 62 may 35 be cut into the end edges of the leaf spring member. It may thus be observed that the leaf-spring and the frame or contact-moving member form a contact operating unit.

In order that an over-center action may be 40 produced, the leaf spring member 60 has an H-shaped slot 64 stamped in its central portion providing two short arms 66 whose ends engage in a circumferential groove formed near the end of an actuator in the form of an operating pin 45 or plunger member 70. To bow the arms 66 and give the leaf spring a bias, the diameter or thickness of the portion of the plunger 70 engaged by the arms 66 is greater than the distance between the ends of the arms 66 in their normal 50 flat aligned state.

At the central portions of the ribs 50, 52 and 54, cylindrical studs 50s, 52s, 54s are affixed. The studs 50s and 54s extend laterally inwardly from one side of the ribs 50 and 54, and the stud 55 52s extends from both sides of the rib 52. These

studs are aligned and are adapted to seat within in the insulating plungers 42 so that upon movement of the frame, the plungers will be caused to simultaneously move downwardly to cause the bridging contacts to disengage the fixed contacts simultaneously.

To guide rectilinear movement of the plunger 10, a diametrical slot 12 is cut into the inner end of the plunger to receive short guide pins 14 radially extending inward from the walls of a central aperture 16 formed in a rectangular cover member 18 for the base 10. The cover member 18 may conveniently be made of molded insulating material and hollowed out on its inner surface for the reception of the operating mechanism.

Normally urging the plunger outward of the cover 18 is a compression spring 82 coiled around the plunger. One end of this spring 82 presses against the under side of a flange 74 formed on the upper and outer end of the plunger 10; the opposite end of the spring presses upon the floor of a circular recess 84 in the cover concentric with the plunger-receiving recess 16. The recess 84 preferably will be the same diameter as the inner flanged end of an insulating button 80 that covers and insulates the outer end of the plunger 10. The flanged end of the button 80 may be secured in the recess 84 by a stamped sheet metal bridge member 86; and the bridge member 86 may be secured to the cover by through-bolts (not shown) which may, if desired, also serve the additional purpose of holding the cover and base together.

In operation, depression of the button 80 and plunger 10 overcomes the spring 82, bending the leaf spring arms 66 through the plane of the leaf spring member 60 from the position of Fig. 1 to that of Fig. 2. This change of state of the leaf spring carries the frame ribs 50, 52, 54 upwardly, allowing the contact biasing springs 40 to move the bridging contacts 38 into engagement with the stationary contacts 22, 24.

Release of the button 80 will permit the return spring 82 to reverse the condition of spring arm 66, forcing the frame down and overcoming the lesser force of contact springs 40 to move the bridging contacts to open position.

Many modifications within the scope of the invention will occur to those skilled in the art. Therefore I do not limit the invention to the embodiment disclosed.

I claim:

1. In an electric switch, a plurality of independent sets of fixed and movable contacts each comprising a pair of fixed contacts and a bridging contact, spring means biasing said bridging contact into closed circuit position, in combination with actuating means comprising a contact-

moving member acting upon said bridging contacts to move them simultaneously, a leaf spring member having an H-shaped aperture providing resilient portions for providing a bias of said spring member into one or another of two conditions, said leaf spring member engaging at its ends with said contact-moving member, and an operating pin engaged by said resilient portions for changing the direction of bias of said leaf spring member.

2. In an electric switch, a casing, a plurality of fixed and movable contacts therein, a contact-moving member acting upon said movable contacts to move them simultaneously, a leaf spring member cooperating at its ends with said contact-moving member and having positions of opposite bias for locating said contact-moving member in spaced positions, means in the bottom of said casing supporting said contact-moving member during change of bias in one direction, means in the top of said casing supporting said contact-moving member during change of bias in the other direction, and a manually operable actuator for changing said bias.

3. In an electric switch, a casing, a plurality of fixed and movable contacts therein, said movable contacts being independently movable, a contact-moving member acting upon said movable contacts to move them simultaneously, a leaf spring member cooperating at its ends with said contact-moving member and having positions of opposite bias for locating said contact-moving member in spaced positions, means in the bottom of said casing supporting said contact-moving member during change of bias in one direction, means in the top of said casing supporting said contact-moving member during change of bias in the other direction, and an actuator manually operable in one direction to change said bias, and spring means operating said actuator to change said bias in the other direction.

4. In an electric switch, a casing, a plurality of fixed and movable contacts therein, said movable contacts being independently movable, a contact operating unit comprising a contact-moving member acting upon said movable contacts to move them simultaneously and a leaf spring member engaging at opposite end portions with said contact-moving member, an actuator engaged by stressed portions of said leaf spring member to provide bias in opposite directions for locating said unit in different positions, means in the bottom of said casing supporting said contact-moving member during change of bias in one direction, and means in the top of said casing supporting said contact-moving member during change of bias in the other direction.

ROBERT H. BENTLEY.
